(57) **CLAIM**

The ornamental design for a pair of swim fins as shown and described.

DESCRIPTION

FIG. 1 is a perspective view of a first embodiment of a pair of swim fins showing my new design;

FIG. 2 is a top view thereof;

FIG. 3 is a bottom view thereof;

FIG. 4 is a left view thereof;

FIG. 5 is a right view thereof;

FIG. 6 is a front view thereof; and

FIG. 7 is a rear view thereof;

FIG. 8 is a perspective view thereof in a state of use; and, FIG. 9 is a perspective view of a second embodiment herein, which is the mirror image, or other foot, of the first embodiment. Mirror images of FIGS. 1-8 constitute various views of the second embodiment herein. A third embodiment is the pair of swim fins made by the combination of the first and second embodiments.

The broken lines in FIGS. 1-7 and 9 depict portions of the pair of swim fins that form no part of the claimed design. The broken lines in FIG. 8 depict environmental subject matter and form no part of the claimed design.
